CLAIM

The ornamental design for a shoe outsole, as shown and described.

DESCRIPTION

FIG. 1 is a top plan view of a shoe outsole showing my new design;

FIG. 2 is a bottom plan view thereof;

FIG. 3 is a right side elevational view thereof;

FIG. 4 is a left side elevational view thereof;

FIG. 5 is a front elevational view thereof; and,

FIG. 6 is a rear elevational view thereof.

The drawing disclosure shows the design for a shoe outsole for a left shoe. It is understood that the right shoe outsole is a mirror image thereof.

The dashed broken lines shown in the drawings are for illustrative purposes only and form no part of the claimed design. The broken dot-dash line(s) define the bounds of the claim and form no part thereof.
